UNITED STATES PATENT OFFICE.

GARRETTSON SMITH AND HENRY BROWN, OF PHILADELPHIA, PENNSYLVANIA, ASSIGNORS TO CHARLES NOBLE & CO., OF SAME PLACE.

DESIGN FOR A STOVE-FRONT.

Specification forming part of Design No. 5,882, dated May 28, 1872.

Specification describing a Design for a Stove-Front, produced or invented by GARRETTSON SMITH and HENRY BROWN, of Philadelphia, Pennsylvania.

Design for the Front of a Stove.

The figure in the accompanying drawing fully represents our design for a curved plate or casting, adapted for attachment to the front of an upright heating-stove.

The upper portion A of the plate is vertical, and the portion B, immediately beneath the same, is inclined outward to the line of beading *a*, where it joins the portion C, the latter being inclined inward to a narrow vertical band, D, which forms the base of the plate. The band D and portion C of the plate are ornamented in imitation of basket-work, and from the opposite edges of the portion B and C extend rounded projections or wings *b b*,

having the scroll-like ornamentation clearly represented in the drawing. The door *d* in the portion A of the plate, and the doors *e* in the portion B are of the ornamental design shown; and the portion A at either side of its door is ornamented by the scrolls and edging *f* and *g*, and at the top it has a scalloped bead, *h*.

We claim—

The design for a stove-front substantially as described, and as illustrated by the accompanying drawing.

In testimony whereof we have signed our names to this specification in the presence of two subscribing witnesses.

GARRETTSON SMITH.
HENRY BROWN.
